Primary Examiner — Marianne Pandozzi*Assistant Examiner* — Jae Liang*(74) Attorney, Agent, or Firm* — Davis Wright Tremaine LLP(57) **CLAIM**

The ornamental design for a drinking apparatus, as shown and described.

DESCRIPTION

FIG. 1 is an environmental perspective view of a drinking apparatus showing our new design;

FIG. 2 is a front perspective view thereof;

FIG. 3 is a rear view thereof;

FIG. 4 is a front view thereof;

FIG. 5 is a right side view thereof;

FIG. 6 is a left side view thereof;

FIG. 7 is a top view thereof; and,

FIG. 8 is a bottom view thereof.

The broken lines in the drawing depict environmental subject matter only and form no part of the claimed design.
